CHESTER A. FRICK, OF MUNCIE, INDIANA, ASSIGNOR TO GLASCOCK BROTHERS MFG. COMPANY, OF MUNCIE, INDIANA, A CORPORATION OF INDIANA.

REFRIGERATOR DRAIN.

Application filed March 11, 1926. Serial No. 93,903.

My invention relates to improvements in draining means for refrigerators and the like. It is particularly designed to provide a drain for tubular receptacles which are adapted to contain liquid.

My invention is especially adapted for use in connection with that type of bottle cooling refrigerator wherein the bottles are passed through substantially U shaped tubular channels for cooling purposes. In this type of refrigerator there is usually provided an outer corrugated tub and an inner corrugating tub nesting the outer tub, the walls of the two tubs being spaced apart to form substantially tubular channels through which the bottles to be cooled are adapted to be passed. The space between the channels is adapted to be filled with a cooling liquid and the inner tub is adapted to contain ice or other refrigerating medium. The drain of my invention is especially applicable to this type of refrigerator as it permits of the normal draining of the inner tub when the water therein attains a predetermined level and at the same time permits of the complete draining of both compartments when desired.

For the purpose of disclosing my invention I have illustrated one embodiment thereof in the accompanying drawings in which

Fig. 1 is a perspective view partially in section of a type of refrigerator with which my invention may be used;

Fig. 2 is a detail section of a part of the refrigerator and of the drain, and

Fig. 3 is a detail partial sectional view showing the drain opened for complete drainage.

The refrigerator of the type illustrated comprises a suitable receptacle or casing 1 in which is mounted a corrugated tub 2 U shaped in cross section, a suitable filler of insulating material being interposed between the tub and the walls of the casing. Suitably supported in nesting position and spaced apart from the tub 2 is an inner corrugated tub 3 substantially U shaped in cross section. This arrangement provides a series of water communicating tubular channels 4 through which the bottles to be cooled may pass. Both tubs are open at their tops. Doors such as 5 are provided for closing the openings to the channels 4 and a cover plate such as 6 is provided for covering the

inner tub. This inner tub provides an ice chamber 7.

For drainage purposes the outer tub 2 is provided with an opening 8 through which projects a drainage tube 9 the upper end of which lies adjacent to the inner tub 3 immediately beneath an opening 10 therein. The tube 9 is provided with an annular flange 11 on which the bottom of the outer tub 2 seats and has an extended nipple 12 internally screw threaded for connection with a drain pipe or suitable drain cock 13. This tube 9 is provided in its sides with drain openings 14 which communicate with the space between the outer and inner tubs. The upper end of the tube 9 preferably has a permanent connection with the bottom of the inner tub 3 and at the annular flange 11 with the bottom of the outer tub 2. This arrangement provides for a drain communicating both with the chamber 7 in the inner tub 3 and with the chamber 4 between the outer and inner tubs 2 and 3.

In normal use of the refrigerator the water in the chambers or tubes 4 is maintained therein. The ice is placed in the inner chamber 7 and as the ice melts it is desirable to have some means for draining the water from this chamber after it reaches a predetermined level. To this end I provide a drain pipe 15 which projects into the drain tube 9 and has a screw threaded end 16 taking into the internal screw threads 17 in the lower end of the tube 9. This drain pipe 15 has an annular collar or flange 18 backed by a collar 19 which flange 18 bears on the inner surface of the inner tub 3 so that when the pipe 15 is screwed down into the tube 9 the inner tub is clamped between the top of the tube 9 and the flange 18. Drain openings 20 are formed at a predetermined point near the top of the drain pipe 15 through which the water from the melting ice of the chamber 7 drains and above these openings there is also provided openings 21 into which a turning pin may be inserted for rotating the pipe to screw it into and out of its socket. It will be noted that this arrangement provides a means for normally draining the inner tub and at the same time when it is desired to empty both the inner tub and the space between the inner and outer tubs it is merely necessary to remove the pipe 15 when the water will flow through the drain tube 9 from both chambers.

I claim as my invention:

1. The combination with a pair of nested tubs each arranged to contain liquid, a drainage tube connected with the bottom of the inner tub and arranged to extend through the bottom of the outer tub and having openings communicating with the outer tub, a second drainage tube telescoping said first mentioned tube and removable 5 threaded therein to close said first mentioned tube and arranged to extend upwardly into the inner tub for draining the inner tub and having means for closing the drainage connection of the first tube with the inner tub.
2. The combination with a pair of nested tubs each adapted to contain liquid, of a drainage tube projecting through the outer tub and having its inner end bearing on the inner tub, an annular flange on said tube engaging the outer tub, a second drainage tube telescopically screw threaded into said first mentioned tube and projecting into the inner tub and an annular flange on said tube bearing upon the inner surface of the inner tub whereby when said tube is in position the wall of the inner tub will be clamped between the end of the first mentioned tube and the collar on said second mentioned tube.
3. The combination with a plurality of nested tubs, of a drain therefor comprising a draining tube having a drainage connection with the bottoms of each of said tubs, of an overflow drain tube associated with said first mentioned tube, said overflow tube co-operating with the first mentioned tube when in drainage position to establish an overflow passage from the inner tub and to close the drainage connections of the first mentioned tube with both tubs, and movable to a position to simultaneously establish drainage connection between both tubs and said first tube.
4. The combination with a plurality of nested tubs, of a drain tube common to all of said tubs and having a drainage connection with each of the same, an overflow drainage tube co-operating with the first drainage tube to establish an independent opening to the inner tub and having means for closing both of the drainage connections of the first mentioned tube with the respective tubs, said drainage tube being movable to a position to establish simultaneous drainage communication between the first tube and both tubs.
5. The combination with a plurality of nested tubs, of a drainage tube common to all of the tubs and having a drainage connection with each of the tubs, of a second drainage tube telescopically insertable in said first drainage tube and having means for closing the drainage connections of the first mentioned tubes with each of the tubs and for establishing an independent drainage connection for the inner tub, said second mentioned tube being removable from position to permit the drainage of both tubs through said first mentioned tube.

In witness whereof I, CHESTER A. FRICK, have hereunto set my hand at Indianapolis, Indiana, this 5th day of March, A. D. one thousand nine hundred and twenty-six.

CHESTER A. FRICK.

I claim as my invention:

1. The combination with a pair of nested tubs each arranged to contain liquid, a drainage tube connected with the bottom of the inner tub and arranged to extend through the bottom of the outer tub and having openings communicating with the outer tub, a second drainage tube telescoping said first mentioned tube and removably threaded therein to close said first mentioned tube and arranged to extend upwardly into the inner tub for draining the inner tub and having means for closing the drainage connection of the first tube with the inner tub.
2. The combination with a pair of nested tubs each adapted to contain liquid, of a drainage tube projecting through the outer tub and having its inner end bearing on the inner tub, an annular flange on said tube engaging the outer tub, a second drainage tube telescopically screw threaded into said first mentioned tube and projecting into the inner tub and an annular flange on said tube bearing upon the inner surface of the inner tub whereby when said tube is in position the wall of the inner tub will be clamped between the end of the first mentioned tube and the collar on said second mentioned tube.
3. The combination with a plurality of nested tubs, of a drain therefor comprising a draining tube having a drainage connection with the bottoms of each of said tubs, of an overflow drain tube associated with said first mentioned tube, said overflow tube co-operating with the first mentioned tube when in drainage position to establish an
- overflow passage from the inner tub and to close the drainage connections of the first mentioned tube with both tubs, and movable to a position to simultaneously establish drainage connection between both tubs and said first tube.
4. The combination with a plurality of nested tubs, of a drain tube common to all of said tubs and having a drainage connection with each of the same, an overflow drainage tube co-operating with the first drainage tube to establish an independent opening to the inner tub and having means for closing both of the drainage connections of the first mentioned tube with the respective tubs, said drainage tube being movable to a position to establish simultaneous drainage communication between the first tube and both tubs.
5. The combination with a plurality of nested tubs, of a drainage tube common to all of the tubs and having a drainage connection with each of the tubs, of a second drainage tube telescopically insertable in said first drainage tube and having means for closing the drainage connections of the first mentioned tubes with each of the tubs and for establishing an independent drainage connection for the inner tub, said second mentioned tube being removable from position to permit the drainage of both tubs through said first mentioned tube.

In witness whereof I, CHESTER A. FRICK, have hereunto set my hand at Indianapolis, Indiana, this 5th day of March, A. D. one thousand nine hundred and twenty-six.
